UNITED STATES PATENT OFFICE

160,693

ROSARY

Cesare Civelli, Rome, Italy

Application December 6, 1949, Serial No. 6,435
In Italy June 10, 1949

Term of patent 14 years

(Cl. D45—16)

To all whom it may concern:

Be it known that I, Cesare Civelli, a citizen of the Italian Republic, residing at Rome, Italy, and having my post-office address at Rome, Italy, Viale Mazzini 106, have invented a new, original, and ornamental Design for a Rosary, of which the following is a specification, reference being had to the accompanying drawings, forming part thereof.

Fig. 1 is a front elevational view of a rosary embodying my new design;

Figs. 2 to 6, respectively, are developed plan views of the five pentagonal-shaped beads forming the pendant element of the rosary from top to bottom as shown in Fig. 1, and

Fig. 7 is an enlarged side elevation of one of the oval beads, with the ornamentation omitted therefrom for convenience of illustration.

I claim:

The ornamental design for a rosary, as shown.

CESARE CIVELLI.
